UNITED STATES PATENT OFFICE.

WILLIAM ERASTUS WILLIAMS, OF WILMETTE, ILLINOIS.

VENDING MACHINE FOR BOOK MATCHES.

Application filed December 10, 1926. Serial No. 153,981.

My invention relates to the coin control or slot machine type and is especially adapted to vending book matches which have previously been prepared by being fastened onto 5 a continuous tape and the latter being wound up into a roll or reel and loaded into a machine as a complete reel or cartridge and the end of this reel of tape loaded with matches is trained from the reel into the 10 mechanism which step by step carries forward a single section of the tape upon which are mounted the books. Thus, at each operation by the coin deposited it is intended to deliver two books of matches to the pur- 15 chaser.

The object of the invention is to provide a machine that will handle and vend book matches mounted on a tape in an efficient and serviceable manner and with the specially arranged desirable details as will be hereinafter set forth.

Reference will be had to the accompanying drawings of which Fig. 1 is a top plan view of the device.

Fig. 2 is a front elevation.

Fig. 3 is a side elevation of the machine.

Fig. 4 is a vertical section on line 4—4 of Fig. 2.

Fig. 5 is an elevation of the tape feeding mechanism which is located in the upper lefthand corner of the machine as referred to in Fig. 4 as seen when the side door is opened.

Fig. 6 is a view similar to Fig. 5 showing the parts in a different position.

Fig. 7 is a plan view of a section of a tape with the books of matches secured thereto.

Fig. 8 is a horizontal section on line 8—8 of Fig. 11.

Fig. 9 is a vertical section showing details of the operating mechanism on line 9—9 of Fig. 11.

Fig. 10 is a horizontal section indicated by the arrows on line 10—10 of Fig. 4.

Fig. 11 is a front vertical section on line 11—11 of Fig. 13.

Fig. 12 is a view similar to that of Fig. 11 but showing the parts in a different position.

Fig. 13 is a vertical section on line 13—13 of Fig. 12.

The machine is adapted to handle and vend matches which have been prepared by 55 being bound together on a tape and the paper strip of tape is shown in Fig. 7 where-

in 2 indicates the strip and 3 the books of matches. This strip is stapled onto the lower ends of the books lying flatwise and the lower ends of the opposite books abutting against each other making a close contact on the tape with the narrow spaces indicated by 4 between the books as relates to the length of the tape; the purpose of this space being to facilitate the handling 60 of the books through the machine. The whole load of matches for a machine consists of a piece of tape loaded with matches of sufficient length that when coiled up as shown in Fig. 4, it is loaded into the machine as a single charge, reel, coil, cartridge, bundle, or package, the coil of matches thus prepared being formed into the package at the factory where the matches are made. The machine is enclosed in a case having 65 base piece 5 composed of wood or other suitable material on which is a metal base wall 6 and the rear end of the case is formed by a solid wall 7 and the left side of the machine as it appears in Figs. 1 and 2 is 70 also a fixed metallic wall 8. The right side of the machine as indicated by Figs. 1 and 2 and the front of Fig. 3 is composed of a door 16 which covers the whole side of the case and is hinged at the back wall by the 75 hinges 9 and this door is provided with an overlapping flange 10 going over the top corners of the case and the side overlapping flange 11 at the front of the machine, see Fig. 2. The top cover piece of the machine 80 is also a hinged member and is composed of the plate 12 hinged on the inside by the hinges 13, Fig. 4, to the side wall 8. The front face of the machine is provided with a casing wall made of two members 85 one of them being indicated in Fig. 2 by 14 which simply is a sort of an idle blank wall more for appearance than enclosure purposes while the right side of the front face is provided with a wall 15 to which 90 part of the coin controlled operating mechanism is secured.

The door members are locked shut by means of an ordinary furniture lock 17 shown in the dotted line of Fig. 3. Bolt 18 105 of this lock extending inside the flange 19 on the front face or wall piece 15. The overlapping flange 10 prevents the raising of the top cover piece 12 when the door 16 is locked.

On the inside of outside walls of the casing there is the semicircular cross member 20

which is a plate which extends across from the door 16 back to the side wall 8 and furnishes a curved bottom for the space in which the coil of match books is located. 5 The front wall 21 of this interior member 20 extends upward and forms as it were, the front face of an inside wall separating the chamber which holds the match books from the chamber in which the coin mechanism is located, this latter chamber being indicated by 22, Fig. 4.

10 A spindle 23 is secured to the side wall 8 of the casing and is arranged to receive the coil or bundle of books of matches and hold 15 them in a manner to be easily unwound as the matches are fed outward by the mechanism of the machine.

Owing to the necessity of having the mechanism which feeds out the tape loaded 20 with books of matches a little wider than the coil of tape for the purpose of accommodating the mechanism which mechanism extends outside of the width of the bundle of matches, the casing is filled outward by 25 pieces of wood or other material being indicated by 24 in Fig. 4 and this may also be observed in Fig. 10. Likewise it is shown in dotted lines in Fig. 3 as relates to the segment of wood which is fastened to the door 30 16.

The mechanism which carries forward the books is composed of a chain the links of 25 which are made of stampings out of flat sheets and provided with flat body pieces 25 and the ends of these body pieces are turned up into end flanges 26 having lugs 27 connected by pins 28 and this chain so constructed is trained over sprocket wheels 29 of pentagon outline having flanges 30 at 40 each end thereof to hold the chain from displacement off the ends of the sprockets. The sprockets 29 are mounted upon shafts 39 carried in bearings on the bars 31 which are connected to the end flanges 32 of a cross 45 member piece 33 between and parallel with the shafts 39 and connects the bars 31 which in turn hold between them the sprockets 29.

Sprockets 29 owing to their pentagon form need no other engagement in the chain links 50 than what is brought about by the angularity of the pentagon faces, the corners 34 of these pentagon faces amounting to what might be termed ordinary sprocket wheels. At the edges of the flat body piece 25 of the links 55 of the chain there are turned up projections 35 out of the body of the metal of the links which projections extend upward in between the spaces 4 between the books as fastened on the tape, and thus secure an engagement of 60 the tape at several points which results in making a secure engagement with the tape of match books, to the end that accidental displacement substantially never takes place, as long as the binding tape between the books is not broken.

At the front or delivery point for the books the front walls 14 and 15 of the case are opened leaving an exposure directly to the base flat piece 25 of the links as indicated by Fig. 4 whereat the books are delivered to be 70 taken by the purchaser as indicated by position 36. At each operation of the machine, which involves one movement of the sprockets 29 one-fifth of a revolution, a book is moved from position 37, see Fig. 4, to position 36 exposing the end of the tape with 75 two books ready to be grasped by the fingers at position 36 and the purchaser then takes hold of these books and tears off the tape which gives him possession of two books. 80

Each of the spring blades 38 is fastened to the hinged cover plate of the machine, as shown in full lines in Fig. 4 and dotted lines in Fig. 1 with a downwardly extending free end for holding down one of the two end 85 books in position 37 to such an extent that when the purchaser takes hold of two books at position 36 and tears off the tape which connects them to the books in position 37, he will get but the two books since the springs 90 38 and the projections 35 prevent more than one set of books being pulled off or out at one time. The mechanism is designed to require a new coin for each partial revolution of the sprocket wheels which causes the delivery of 95 one section of the match book loaded tape at a time.

One merit of using a chain in the manner shown for carrying forward the tape loaded 100 with match books lies in the fact that regardless of how many books there may be remaining at the exhaustion of the load the chain will carry even the last book to the position for final delivery.

For the purpose of giving notice to the 105 purchaser of the exhaustion of the supply of books in the machine and thus warn him against undertaking to deposit a coin when there are no books to be delivered, I provide a small glass window 40 in the top cover 110 piece 12 of the case and in some instances I provide a similar window in the region indicated by 41, see Fig. 4. The movement of the sprockets 29 in a step by step manner is brought about by the pins 42, see Fig. 5, 115 which are engaged by a pawl block 43 having a shoulder 44 and a vertical face 45 and hinged at 46 to a vertical plunger rod 47 of angular cross section which rod 47 is provided with a protruding thumb piece 48 120 which the operator presses down after having inserted the coin in the crescent coin slot 49 in front of the machine, see Fig. 2. The vertical movement of this plunger rod 47 is such that the projection 44 engages one 125 of the pins 42 and pushes it downward amounting to the angular distance of one-fifth of a revolution of the sprockets 29.

The sprocket at the front of the machine, the flange 30 of which is provided with the 130

pins 42, is the controlling sprocket for the movement of the chain and a detention pawl 50 is hinged at 51 to one of the cross members 33 which supports the sprockets in the frame 5 and pawl 50 prevents a retrograde movement of the chain by a catch 52 shown in dotted lines in Fig. 5 and engages one of the pins 42 and prevents a retrograde movement of the sprockets and chain. On a forward 10 movement of the sprockets and chain the inclined surface 53 of this pawl 50 rides over the pins 42 and drops by gravity down over the pins to lock them against retrograde movement. A similar pawl 54 hinged at 15 55 to this same cross member piece 33 is provided with a catch lip 56 shown in dotted lines that engages at intervals the pins 42 and locks the sprocket shown from movement of more than one space at a time. The 20 position shown in Fig. 5 is that of repose at the completion of the delivery of one charge of books, the mechanism being ready for the beginning of a new operation. Thus it will be observed that the sprockets and 25 chain are locked in position of Fig. 5 against movement in either direction. The pawl 50 automatically operates by gravity by virtue of the heavy end extending from its hinge 51 but the pawl 54 is actuated in its movement by a bar 57 hinged at 58 to the said pawl 54 and this bar 57 is connected to the mechanism to be actuated by a coin when same is inserted in the coin slot 49 as previously mentioned. By referring to Fig. 6 30 the position of the pawl 43 is shown in the act of moving the sprockets and chain and thus it will be noticed in this figure that the pawl 54 has cleared the pin 42 which in the position of Fig. 5 was engaged by the catch lip 56. On the completion of the movement 35 downward of the plunger rod 47 a complete movement is made for one chain link delivering the two books to the position or discharging face 36, see Fig. 4. Upon the completion of this downward movement of rod 47 and the release of the finger or thumb piece 48 by the operator or purchaser a spring automatically returns the plunger or rod 47 to the position of Fig. 5. Prior to the 40 commencement of the return movement of rod 47 the bar 57 has returned from the position of Fig. 6 to that of Fig. 5 and thus restores the pawl 54 to the initial position to prevent more than one link of the chain 45 going forward at the single release. Thus the operator may not push the thumb piece down and then catch hold of the extending edge of the exposed pair of match books in the position of 36 and then continuously 50 pull out the entire supply of matches as this is prevented by the pawl 54 dropping immediately back in place whenever one of the pins 42 passes sufficiently forward to carry a book far enough outward for a person to 55 grasp the books or the chain itself and pro-

duce, as it were, a robbery of the machine. The pawl 43 hinged at 46 is controlled by a small spring 59, see Figs. 5 and 6, which keeps the pawl in position to engage the pins 42 and at the same time on the return stroke 70 of the plunger rod 47 allow the inclined surface 60 to spring past one of the pins 42 and get again in position of Fig. 5 ready for the shoulder 44 again to engage a pin 42 on another downward movement. The 75 position of the pawl 43 is sustained in the limited movement required by means of a small pin 61 in the bar 47 engaging a slot 62 in the pawl 43. The space between the shoulder 44 and the pin 42 immediately below it allows sufficient movement of the bar 47 when a coin has been inserted in the coin slot 49 to permit the coin to act as part of the mechanism in releasing the latch device which limits the movement of the bar 47 save 80 only when a coin is present to release this latch. This mechanism is best illustrated in Figs. 8, 9, 11, 12, and 13.

It is substantially necessary to provide in slot machines that a complete movement be 90 made of the operating mechanism at each interval in order to prevent a displacement of the parts and to insure the delivery of what is expected to be made, and to insure this feature of a complete movement, the 95 bar 47, as before described, being in form of an angle in the cross section has upon its leg at right angles to that shown in Figs. 5 and 6 a section of teeth 63, see Fig. 11, which is engaged by a pawl 64 hinged at 65 100 and controlled by a spring 66 to hold the pawl in engagement with the teeth in either direction of movement of the bar 47, clearance space 67 being provided at each end of the section of teeth to allow a reversible 105 movement of the pawl 64. Thus in pushing down the bar 47 by the thumb piece 48 the pawl 64 will make it necessary for a complete stroke to be made before a return movement may be accomplished and then on the 110 upward movement of the bar 47 the pawl 64 reverses its action and prevents any return movement until a full up stroke is completed. Thus there is guarded against a pumping of a slot machine and a resulting 115 fraudulent operation thereof. The upward movement of the bar 47 is brought about by a spring 68 one end of which is secured at 69 to the screw 70, Fig. 13, and the lower end secured at 71 to the lower end of the 120 bar 47. Thus whenever the operator releases the pressure on thumb piece 48 the spring 68 automatically returns the bar, provided, of course, any movement of the bar 47 has been downward sufficiently to permit 125 the pawl 64 to enter the upper clearance space 67 which has only been arrived at after the right movement of the bar 47 has taken place to complete one operation of the sprockets and chain as previously mentioned. 130

The mechanism which is controlled by a coin when one is entered into the coin slot 49 is best shown in Figs. 11 and 12 wherein 72 indicates the coin which has just been 5 entered into the coin slot and drops down into a coin chute, being indicated by the shaded portion 73. As the coin is entered into the slot its movement into the coin chute 73 is arrested by a block 74, see Fig. 11, and this position of the coin is immediately under the projection 75 of the block 76 secured to the plunger rod 47. As the plunger rod 47 is pushed downward a portion of its movement being the distance between the shoulder 44 and the pin 42 in Fig. 5 the coin 72 is carried down by the projection 75 and pushes the block 74 to the left, the extreme position of this movement being indicated by Fig. 12 and as this block 20 74 is secured to a bell crank lever 77 hinged at 78 the block 74 moves the bell crank lever 77 and in this movement from the position of Fig. 11 to that of Fig. 12 there is brought about the lifting of the bar 57 which releases the pawl 54 from one of the pins 42 as previously described as the bar 57 is connected at 79 to an arm 80 of the bell crank lever 77.

The movement of the bell crank lever 77 30 from the position of Fig. 11 to that of Fig. 12 results in lifting the bar 57. Not only that, the upper end 81 of the bell crank lever 77 is connected by a pin 82 to a locking bolt 83 one end of which is carried on a pin 84 secured into the front wall 15 of the casing and engages a slot 85 in the said latch 83. The outer end 86 of the said latch 83 in the position shown in Fig. 11 extends in front of one leg of the angle sectional plunger 47 and is in position to engage a small spring 87 which extends through the slot 88 in the leg of the plunger 47. This spring 87 is adapted to hit against the end 86 of the latch 83 and prevent a movement of the plunger 47 down past the latch 83 until after the latch 83 has been moved to the left to the position indicated in Fig. 12 wherein the end 86 of the latch 83 has been moved out of the pathway of the spring stop 87 and thus 40 in that position of the latch 83 the bar 47 may be pushed downward further carrying the coin down through and out of the coin chute 73 where it will fall down into the space 89, see Fig. 4, which is a storage place 45 for the coin access to which is had only when the door 16 is open. A spring 90 secured at 91 to the bell crank lever 77 and secured at 92 to the front wall 15 of the case returns the bell crank lever 77 from the position 50 shown in Fig. 12 to that shown in Fig. 11 and this action immediately takes place as soon as the bar 47 passes downward bringing the stop spring 87 below the region of the end 86 of the latch 83 and thus the return 55 of the bell crank lever 77 brings about the

return of the pawl 54 to position to catch the next pin 42 coming along so that substantially on the instant that the coin 72 gets below the contact of the block 74 the pawls 54 and 50 are in position to prevent 70 a false movement of the sprocket chain before the completion of the movement of the plunger 47 that permits the delivery of a single set of match books and on the return movement of the plunger 47 under the influence of the spring 68 the stop spring 87 springs past the end 86 of the latch 83 and thus allows the bell crank 77 to function in returning the locking bolt 83 before the plunger 47 has returned upward to its normal position ready for another operation. 80

In machines heretofore used for vending book matches considerable time is employed by the person who reloads the machine since the books must be placed in the box one by one. With my machine the load of books comes as a complete coil package prepared in the factory and the operator opens the main side door 16 and raises the top door wall 12 and then has a clear open space in 90 which to insert the cartridge or coil of match books, see Fig. 4, sideways onto the spindle or supporting stop 23 and at that time the lid or top piece 12 is raised out of the way and he easily drops down the upper end 95 of the tape loaded with books in the proper position onto the chain and then returns the top lid 12 to the position shown in Fig. 4, and then shuts and locks the door 16 and the machine is ready for operation. 100

The top flange 10 of the door covers over the top edge of the cover plate 12, the latter is stiffened by a flange on its side edge indicated by dotted lines 93 in Fig. 3 and in full lines in Figs. 5 and 6. The flange 11 on 105 the front edge of the door 16 is cut away in the region where the thumb piece 48 moves, see Fig. 2, to the limit or bottom 94 of the stroke of the thumb piece 48. Thus the thumb piece 48 moves from the position 110 shown in Fig. 1 down until the piece 47 hits the edge 94 of the flange 11 which is that stroke required for one complete operation of the machine.

Thus by the construction shown whenever 115 a coin is entered and the thumb piece 48 is pushed down carrying its plunger 47 for the full limit of the stroke there is delivered at position 36 a pair of books which may be torn off from the tape or the tape torn off 120 itself at that point and then the remaining piece of tape torn from the book giving the purchaser two books of matches.

These matches are usually placed upon counters of cigar stores and other places 125 where tobacco products are sold and it is desirable that the frontage of the counter be conserved as much as possible and the machines be as narrow as possible as relates to taking up counter or show case frontage. 130

This machine which is narrow and relatively deep perhaps is less objectionable than a machine which has a wider front face and may extend for a shallower distance over the showcase. Thus in this respect this machine occupies less space which is serviceable to the merchant and permits more useful space in the counter or showcase for other purposes than the old slot machines. Not only that, many of the locations of these machines are in places where the salesman or clerk is busily employed with customers and his time is more valuable in serving other merchandise more so than it is more in serving the customer with matches, since the old styled machines require a lot of handling of match books as individual books and consumes a lot of time in loading. This machine may be loaded as a single unit in a very short time. This machine will hold upward of 200 books without occupying any more actual cubic space than the old styled machines which only hold about 40 to 50 books besides having the further advantage of occupying so much less counter frontage than do the old machines. These facts are controlling factors as relates to match vending machines of this class and every feature of the mechanism which conserves this space as by the arrangement I have shown is a valuable feature contributing to the final success of the machine.

While I have shown and described book matches secured to tape in reel or coil form I may use, when desired, small boxes of matches particularly those of the safety box type which are generally carried in the pockets of the consumer. While I have shown the tape secured to the books by stapling, I may secure them by pasting the strip to the books or pasting them to the boxes whichever manner is most desirable for the purpose required.

I have disclosed novel features in this application which are also disclosed in my co-pending applications Ser. Nos. 89,194 and 155,605.

What I claim is:—

1. In a machine of the class described, the combination with a casing having a door opening broadly at one side and a top cover opening upward enclosing a chamber adapted to carry a reel of match books connected

together by a tape and provided with a delivery orifice, of a feeding mechanism consisting of a chain running over sprockets and having projections which enter in between the sets of match books for delivering books through said delivery orifice, and mechanism for causing a step by step movement of feeding forward the said chain and the said matches to the said delivery orifice.

2. In a machine of the class described, the combination with a casing having a chamber adapted to hold a reel of match books secured together on a tape, of a feeding mechanism for feeding forward the said tape composed of a sprocket chain and two sprocket wheels and said chain provided with projections adapted to enter in the spaces between the books as secured on said tape, and a reciprocating mechanism adapted to move the sprocket wheels a single sprocket at a time.

3. In a machine of the class described, the combination with a casing opening at the side and provided with a chamber adapted to hold a reel of matches secured together by a tape and said chamber having a curved bottom to facilitate the unwinding of the tape and matches from a reel of the same loaded in the said chamber, of a feeding mechanism located above the chamber in which the said matches are located and a cover over the top of the feeding mechanism, said cover adapted to be raised and lowered in gaining access to the feeding mechanism and a side door opening to the said chamber wherein the matches are loaded.

4. In a machine of the class described, the combination with a casing having a chamber adapted to hold a reel of matches secured together by a tape and said casing provided with an opening at the side and having a cover therefor, of a feeding mechanism located above the said chamber and also provided with a suitable cover therefor, clamping means secured on the inside of the said cover over the said feeding mechanism adapted to hold the matches down onto the feeding mechanism when the top cover is closed.

Signed at Chicago, in the county of Cook and State of Illinois, this 8th day of December, 1926.

WILLIAM ERASTUS WILLIAMS.
